QUICK START AND STOP DRIVE MECHANISM FOR PHONOGRAPH TURNTABLES

Lincoln Thompson, Cheshire, Conn., assignor to
to The Soundscriber Corporation, New Haven,
Conn., a corporation of Connecticut

Application April 10, 1941, Serial No. 387,893

10 Claims.

(Cl. 274—9)

This invention relates to phonograph machines for transcribing records of the disc type, and more particularly to a mechanism for driving the record supporting turntable, together with means for permitting said turntable to be quickly started and stopped.

One object of this invention is to provide an improved start and stop mechanism of the above nature which will include a light low-inertia turntable, a heavy motor-operated driving plate, and a friction slip clutch ring located therebetween.

A further object is to provide a device of the above nature which will be simple in construction, inexpensive to manufacture, easy to install and manipulate, compact, ornamental in appearance, and very efficient and durable in use.

With these and other objects in view, there has been illustrated in the accompanying drawing two forms in which the invention may be conveniently embodied in practice.

In the drawing:

Fig. 1 is a schematic view of the invention showing in cross-section the record supporting turntable in cooperating relation with driving and braking means therefor, and showing diagrammatically the remainder of the apparatus and electrical control circuits.

Fig. 2 is a top plan view of the record-supporting turntable.

Fig. 3 is a diagrammatic view of a modified form of the invention.

This invention is an improvement over that disclosed in applicant's copending application, Serial No. 242,598, filed November 26, 1938, entitled "Quick start and stop mechanism for phonograph turntable," patented April 29, 1941, No. 2,240,320.

The present invention is of particular importance for use in the transcriber of a disc type dictating machine for it enables the record to be started and stopped with extreme rapidity without stopping the motor, which runs continuously. It may also be used to reproduce news messages such as are recorded on phonograph disc records in newspaper offices where such messages are received over the telephone or radio.

Referring now to the drawing wherein like reference numerals designate like parts throughout the several views, the numeral 10 denotes a light-in-weight turntable formed of low density, tough, plastic material such as "Bakelite." The turntable 10 is circular and is provided with an annular depending flange 11 about its periphery and a square upstanding central post 12. A disc record 13, preferably of aluminum, having a square opening at its center to fit over and be centered by the

post 12, is adapted to be supported on the turntable 10 in position to have its sound grooves engaged by the needle 14 of an electrical pick-up member 15. The pick-up member 15 is adapted to swing freely across the record 13 and is connected by conductors 16 and 17 to an audion amplifier 18 for operating a loudspeaker, or other sound producing device 19, which is connected to said amplifier by conductors 20 and 21. Electrical energy may be supplied to the amplifier 18 from line wires L1 and L2 by conductors 22 and 23 leading to a separable plug and socket 24 and 25.

A continuously running motor 26 is operably connected to a vertical shaft 27 by means of a flexible coupling 28. The shaft 27 extends upwardly through a bearing 29 rigidly mounted in the machine frame and has a relatively heavy thick circular driving disc, or plate 30, secured thereto by a set screw 30a. The driving plate 30 has its top outer surface cut away to provide a vertical annular shoulder 31 about which a narrow ring 32 of friction material such as cork, is fitted and cemented, said ring being of rectangular cross-section and having its upper surface raised slightly above the upper surface of the plate 30 and adapted to frictionally engage the under surface of the turntable 10.

The shaft 27 is provided on its upper end 33 with an anti-friction collar 34, such as graphite, which collar is surrounded by a hollow conical hub 35 formed integral with the turntable 10 to form a bearing for the upper end 33 of the shaft 27.

Provision is also made of a screw 36 having an upper head 37 disposed in a circular counterbore 38 provided in the square post 12. The shank of said screw extends downwardly from said head and is screw-threaded into the upper end 33 of the shaft 27, whereby the turntable 10 will be maintained in operating position. The shank of the screw 36 is provided with a shoulder 39 which is adapted to seat against the upper end 33 of the shaft 27.

By means of the above construction, it will be obvious that the rotation of the shaft 27 by the motor 26 will drive the turntable 10, and the record 13 mounted thereon, by means of the frictional engagement between the narrow cork ring 32 and the undersurface of the turntable 10. It will also be seen that the light-weight turntable 10 possesses very low inertia and may be instantly stopped by the application of a relatively small braking force to the flange thereof, as hereafter described. The plate 30 being relatively heavy in

weight, and consequently possessing high inertia, will continue to rotate without appreciable decrease in speed whenever the turntable is stopped by means of the brake, and when the brake is released, the turntable by reason of its low inertia will resume its full operating speed substantially instantaneously.

In order to momentarily stop the rotation of the turntable whenever desired, provision is made of a brake shoe 40, preferably made of a leather collar fitted upon the upper end of an upstanding brake rod 41 in position to engage frictionally against the outside surface of the depending flange 11 of the turntable 10. The brake rod 41, in this instance, is pivotally secured to the lower arm 42 of a fixed U-shaped electromagnetic core which is adapted to be energized by current passing through a coil of wire 43, surrounding the vertical base of said core. The coil 43 is connected by a conductor 44 to one terminal of a switch 45, and by another conductor 46 to a current rectifier 47, the other terminal of the switch 45 being connected by a conductor 48 to said rectifier 47. The rectifier 47 receives alternating current from a pair of conductors 49 and 50, leading to the line wires L1 and L2. The upper arm 51 of the electromagnetic core is disposed adjacent the brake rod 41, and is adapted to attract the brake rod 41 whenever the coil 43 is energized to force the brake shoe 40 against the flange 11 of the turntable 10 to stop instantly the rotation of the same—the coil 43 being energized by manual closure of the switch 45, which may be operated by the hand or foot of the operator. A spring 52 reacting between the brake rod 41 and a stationary post 53 is tensioned to constantly urge said brake rod 41 away from the magnet arm 51, so as to release the braking action of the brake shoe 40 on the turntable 10, automatically, whenever the operator releases the switch button 54 to open the circuit. The switch 45 is adapted to be automatically opened by a compression spring 55.

In the modified form of the invention shown in Fig. 3, the switch 45 will be normally held in closed position by a spring 55a, and is arranged to be opened manually by depressing the push button 54a whenever it is desired to start the turntable into rotation. In each form of the invention the motor 26, the rectifier 47 and the amplifier 18 are simultaneously controlled by a manual switch 56 located in the conductor 23 leading to the plug 24.

It will be understood that the friction between the large diameter narrow cork ring 32 and the turntable 10 will be slight enough so that when the turntable 10 is stopped by the brake shoe 40, the motor 26 and the plate 30 will not be materially impeded, but will continue to rotate at substantially full speed. Such friction, however, should be sufficient to insure the practically instantaneous starting of the light turntable 10 at full speed when the brake shoe 40 is disengaged from the turntable flange, and without being retarded by the work required to move the needle in the groove of the disc record.

It will be understood that in the operation of the modified form shown in Fig. 3, whenever the switch 56 is closed to turn on the current the motor 26 will cause the turntable 10 to start rotating immediately, but that the brake 40 will not at first engage the turntable flange since it takes an appreciable time to warm up the tubes of the rectifier 47. When however these tubes have become fully heated, the brake rod will be actuated to stop the turntable. This action may

be utilized by the operator as a definite signal to indicate that the machine is then ready to start transcribing.

One advantage of the use of the present slip friction clutch ring of relatively large diameter is that it will serve to give a more stabilized support to the turntable, and will render the latter less likely to tip or rock without the use of an excessively long central spindle.

10 While there has been disclosed in this specification two forms in which the invention may be embodied, it is to be understood that these forms are shown for the purpose of illustration only, and that the invention is not to be limited to the 15 specific disclosure but may be modified and embodied in various other forms without departing from its spirit. In short, the invention includes all the modifications and embodiments coming within the scope of the following claims.

20 Having thus fully described the invention, what is claimed as new and for which it is desired to secure Letters Patent, is:

1. In a phonograph, a continuously rotating driving plate of high inertia, a low inertia turntable for supporting a disc record having a short flange covering said plate, a solenoid-operated brake rod carrying a brake shoe positioned adjacent said flange to engage it and stop the rotation of said turntable, a friction ring of relatively large diameter mounted on said plate for engaging the undersurface of said turntable, said ring acting as a slip-friction clutch between said plate and said turntable.

2. In a phonograph, a continuously rotating driving plate of relatively high inertia, a turntable of low inertia for supporting a disc record located above said plate, a manually operated brake rod for engaging said turntable to stop the rotation thereof, a slip-friction clutch ring carried by said plate for engaging and supporting said turntable, the friction between said ring and said plate being low enough so that the stopping of said turntable by said brake rod will not stop the rotation of said plate, but high enough to cause said turntable to assume full speed rotation instantly when said brake rod is released.

3. In a phonograph, a continuously rotating driving plate, a turntable of low inertia for supporting a disc record located above said plate, a manually operated brake rod for engaging said turntable to stop the rotation thereof, a narrow slip-friction clutch ring of relatively large diameter carried by said plate for engaging and supporting said turntable, the friction between said ring and said plate being small enough that the stopping of said turntable by said brake rod will not stop the rotation of said plate, but large enough to cause said turntable to assume full speed rotation instantly when said brake rod is released.

4. In a phonograph transcriber, a continuously rotating driving plate, a turntable of low inertia for supporting a disc record located above said plate, a brake rod for engaging said turntable to stop the rotation thereof, a narrow slip-friction clutch ring of rectangular cross section and relatively large diameter carried by said plate for engaging and supporting said turntable, the friction between said ring and said plate being of such magnitude that the stopping of said turntable by said brake rod will not stop the rotation of said plate, and to cause said turntable to resume full speed rotation instantly when said brake rod is released.

5. In a phonograph, a continuously rotating driving plate, a turntable of low inertia for supporting a disc record located above said plate, a manually operated brake rod for engaging said turntable to stop the rotation thereof, slip-friction clutch means of relatively large diameter carried by said plate and located adjacent the periphery of said plate for engaging and supporting said turntable, the friction between said means and said plate being such that the stopping of said turntable by said brake rod will not stop the rotation of said plate, and that said turntable will resume full speed rotation when said brake rod is released, said means extending above the surface of said plate.

6. In a phonograph, a turntable of relatively low inertia for supporting a disc record, a continuously rotating heavy thick plate for driving said turntable, clutch carried by said plate for engaging and supporting said turntable rigidly without tipping, said clutch being of relatively large diameter and small in area so as to have only a slight upper surface to afford a stable frictional support for said turntable, a manually operated brake for engaging said turntable to stop the rotation thereof, the friction between said clutch and said turntable being sufficient to cause the latter to resume full speed rotation instantly when said brake is released.

7. In a phonograph, a continuously rotating driving plate, a turntable of low inertia for supporting a disc record located above said plate, a brake rod for engaging said turntable to stop the rotation thereof, slip-friction clutch means carried by said plate for engaging and supporting said turntable, said means being flat and of sufficient size that the stopping of said turntable by said brake rod will not stop the rotation of said plate, and yet causing said turntable to resume full speed rotation instantly when said brake rod is released, said plate having its outer portion cut away to provide a shoulder for receiving said clutch means.

8. In a phonograph, a continuously rotating driving plate, a turntable of low inertia for supporting a disc record located above said plate, a brake rod for engaging said turntable to stop the rotation thereof, a narrow slip-friction clutch of relatively large diameter carried by said plate

for engaging and supporting said turntable, the friction between said clutch and said plate being such that the stopping of said turntable by said brake rod will not stop the rotation of said plate, and yet said turntable will be caused to resume full speed rotation instantly when said brake rod is released, a motor driven shaft for driving said plate, and a headed screw connected to the top of said shaft to hold said turntable in operating position.

9. In a phonograph, a continuously rotating driving plate of relatively high inertia, a turntable of relatively low inertia for supporting a disc record located above said plate, a manually operated brake rod for engaging said turntable to stop the rotation thereof, friction means carried by said plate for engaging and supporting said turntable, the friction between said means and said plate being such that the stopping of said turntable by said brake rod will not stop the rotation of said plate, and yet causing said turntable to resume full speed rotation instantly when said brake rod is released, a motor-driven shaft for driving said plate, and a headed screw connected to the top of said shaft to hold said turntable in operating position, the central part of said turntable having a depending hub carrying a bearing bushing to embrace the top of said shaft and centralize said turntable.

10. In a phonograph, a continuously rotating driving plate of high inertia, a low inertia turntable for supporting a disc record having a short flange covering said plate, a solenoid-operated brake rod carrying a brake shoe for engaging said flange to stop the rotation of said turntable, a friction ring mounted on said plate for engaging and supporting the undersurface of said turntable, said ring acting as a slip-friction clutch between said plate and said turntable, a tube operated rectifier for operating said solenoid to attract said brake rod and stop the rotation of said turntable, and means to cause rotation of said turntable initially before the tubes of said rectifier heat up,—the stopping of said rotation when the solenoid coil is energized after the heating of said tubes serving as a signal that the machine is ready for transcription.

LINCOLN THOMPSON.
